UNITED STATES PATENT OFFICE.

FRANK J. SCHRAEDER, JR., OF WHEATON, ILLINOIS.

HOISTING APPARATUS.

1,256,932.

Specification of Letters Patent. Patented Feb. 19, 1918.

Application filed February 14, 1914. Serial No. 818,630.

To all whom it may concern:

Be it known that I, FRANK J. SCHRAEDER, Jr., a citizen of the United States of America, and resident of Wheaton, DuPage county, Illinois, have invented a certain new and useful Improvement in Hoisting Apparatus, of which the following is a specification.

This application is subordinate to my 10 prior application Serial No. 723,087, filed September 30, 1912, in which I have claimed my invention broadly.

My invention relates to hoisting apparatus of the kind used, for example, in transferring coal from a storage bin to a car or boat, or to the tender of a locomotive.

An object of my invention is to provide a novel construction and arrangement for 15 enabling the hoisting bucket to descend into the loading pit, move toward the discharge gate of the bin, automatically receive the load, and then move away from the bin and upward.

A further object is to provide improved 20 means for facilitating the discharge of the load when the bucket arrives at the proper point above.

It is also an object to provide certain 25 details and features of construction and combinations tending to increase the general efficiency of a hoisting apparatus of this particular character.

To the foregoing and other useful ends, my invention consists in matters hereinafter 30 set forth and claimed.

In the accompanying drawings—

Figure 1 is a side elevation of a hoisting 35 apparatus for transferring coal from a bin or hopper to a storage bin above, embodying the principles of my invention.

Fig. 2 is a detail sectional view, on a 40 larger scale, of a portion of the bucket, showing the same in engagement with the means by which the contents of the bucket 45 are automatically discharged into the chute or spout by which the coal is then conveyed to the storage bin.

Fig. 3 is a side elevation, on a larger scale, 50 of the bucket in position to receive its load from the bin or hopper, and showing the walls of the pit and bin in section.

Fig. 4 is a front elevation of one-half of the bucket and tilting support therefor, and the adjacent lower end portion of one of the 55 vertical guides or tracks, looking in the di-

rection indicated by the arrows 4—4 in Fig. 3.

Fig. 5 is a view looking down on the devices shown in Fig. 4, as indicated by the arrows 5—5 in Fig. 3. 60

Fig. 6 is a detail sectional view on line 6—6 in Fig. 5.

As thus illustrated, my invention comprises a concrete bin or hopper A for receiving the coal from the car B. This bin has 65 a discharge spout a which is normally closed by the curved gate C, which latter is rigidly secured to the sides of the tilting support c, this support having an axis c¹ about which it swings up and down, said axis being horizontal. The gate C is curved about said axis, and is held normally closed by a rope small c² operated by a weight c³ at the other side of the pit D in which the gate and its support are located. It will be seen that the 70 sides c⁴ of the support are spaced apart to receive the bucket E between them, said bucket having its sides provided with wheels e for engaging the depressed tracks e⁵ with which the edges of the sides c⁴ are provided. 80

These wheels also move up and down in the vertical tracks or ways F, which latter are provided with lower portions f and f¹ which are deflected toward the bin or hopper. Said bucket has its bottom provided with a rigid framing e¹ to which is secured a cross rod e², said rod having reduced portions e³ adapted to drop into the cavities of the bearings e⁴ on the support e⁵ at the bottom of the pit. When the 85 bucket tilts forward upon the support c, as shown in Fig. 3, the portions e³ rotate to an extent which makes it impossible for the rod e² to be raised out of the bearings e⁴ should any attempt be made to do this. 90

Vertically disposed bars G have their lower ends mounted to turn on the rod e², and have their upper ends connected together by a rod or shaft g, which latter carries a sheave g¹ that constantly bears against the rope or cable H which is secured to the bucket at h, and by which the bucket is raised and lowered. The upper ends of the bars G are 100 provided with wheels g² that engage the tracks or ways F and are never disengaged 95 therefrom. Thus the sheave g¹ holds the cable H in position when the bucket leaves the tracks F and tilts forward to receive the load. The gate C is automatically opened 105 by the weight of the bucket, and any suit-

110

able means can be employed for limiting the downward motion of said gate. As soon as the hoisting cable H is operated the bucket tilts back to a position where the 5 wheels e thereof engage the track portion f^1 , and the continued operation of the cable then serves to pull the bucket upward.

The arrangement for discharging the load from the bucket is as follows:—The said 10 bucket has its side provided with a door I pivoted at i at its upper edge, and provided on its side edges with wheels i^1 of any suitable character. A retainer i^2 is pivoted on the bottom of the bucket at i^3 , through the 15 medium of brackets i^4 , and adapted to bear flatwise against the door I when the latter is closed. As the hinge connection i^3 is disposed above the lower end of the door I , the internal pressure of the coal against 20 said door tends to keep the retainer i^2 in a vertical position. The said retainer is provided with side walls i^5 having cam edges i^6 that engage the wheels i^1 on the door of the bucket. These edges are of such shape, 25 it will be seen, (see Fig. 2) that they hold the door open when the retainer i^2 is in the position shown in Fig. 2, whereby the coal may be discharged into the spout or chute J leading to the bin K provided for the 30 storage of the coal. The retainer i^2 is automatically brought into this position by the cam tracks L which have open ends l for receiving the rollers or wheels i^7 on the sides 35 of the retainer. In this position the retainer i^2 also serves as a discharge spout for the bucket, being inclined downward at an angle substantially the same as that of the spout or chute J , or in any suitable manner. When the bucket is lowered, the 40 cam tracks L operate the retainer i^2 in a direction to close the door I , but because of the cam edges i^6 the door closes in time to prevent interference with the upward movement of the said retainer. When the 45 walls and the retainer i^5 and i^2 are in the position shown in dotted lines in Fig. 2, when the door I is thus closed, the weights i^8 on said walls serve to hold the retainer in the vertical position thereof. The rollers or 50 wheels i^1 bear against the cleats M , when the bucket is in the pit, to keep the door of the bucket closed.

Thus it will be seen that when the bucket is raised from the pit the gate C is automatically closed, by upward movement, to prevent the further discharge of coal from the hopper. The bucket then takes the tracks very readily and with absolute certainty, as the sheave g^1 retains the hoisting 55 cable in operative position during the loading of the bucket, and the bucket and sheave then travel upward together. At a point above the load is then automatically discharged from the bucket in the manner described.

An important consideration of my invention is as follows:—In practice, it is desirable to have the bucket pit as small as possible, thus reducing the cost of installation. I accomplish this result in greater measure 70 than is possible with certain other forms of hoisting apparatus, for the reason that the tilting bucket construction is combined with the laterally deflected lower end portion of the track. The deflecting of the 75 track toward the bin tends to reduce the depth of the pit, and the tilting of the bucket then tends to further reduce the depth, as this makes it unnecessary for the bucket to go deeper into the ground to get 80 under the discharge spout. In other words, the pit is not as deep as would necessarily be the case, in order to conform to practice in other respects, in any structure without these features, or with either one of them 85 alone.

As a matter of further improvement, the bucket door I may have its lower end provided with a horizontal bar i^9 that bears against the retainer i^2 to keep the pressure 90 below the axis of the retainer. In this way, the internal pressure of the load is exerted on the retainer in a manner not only calculated not to open the same, but also in a way tending to close the same. The weights 95 i^8 , as stated, tend to keep the retainer closed, and this action is augmented by the internal pressure, in the manner stated.

I do not limit myself to the exact construction shown and described.

What I claim as my invention is:—

1. A hoisting apparatus comprising a bucket, a flexible connection for raising and lowering said bucket, attached to the upper end thereof, a bail hinged to the lower end 105 of said bucket, at the rear side thereof, a sheave for holding said connection in position, mounted on the upper end of said bail, a track, wheels for engaging said track, also mounted on the upper end of said bail, 110 and a support for maintaining said bucket in loading position.

2. A hoisting apparatus comprising a bucket, a track on which said bucket travels up and down, a connection for raising and 115 lowering said bucket, means for discharging into said bucket, a support for causing the bucket to move toward said means, a guide for said connection, and a carrier for said guide, having means for engaging said track, hinged at its lower end to said bucket, 120 said support being pivoted to swing about a fixed horizontal axis, a discharge gate rigid with said support, and means for automatically lifting said support and gate 125 when the bucket is raised.

3. A hoisting apparatus comprising a track, a bucket movable up and down said track, a flexible connection for raising and lowering said bucket, a bail for said bucket,

- hinged thereto, a sheave for engaging and holding said connection in position, carried on the upper end of said bail, a support for holding the bucket in loading position, said support being pivoted to swing about a fixed horizontal axis, a discharge gate rigid with said support, and means for automatically lifting said support and gate when the bucket is raised.
4. A hoisting apparatus comprising a track, a bucket movable up and down said track, a flexible connection for raising and lowering said bucket, a sheave for engaging and holding said connection in position, an element hinged to said bucket, connected with said sheave, and a support for maintaining the bucket in loading position, said support being pivoted to swing about a fixed horizontal axis, a discharge gate rigid with said support, and means for automatically lifting said support and gate when the bucket is raised.
5. A hoisting apparatus comprising a bucket, a flexible connection for raising and lowering said bucket, means for directing the course of the bucket, a guide for said connection, hinged to said bucket, held to a definite path of travel by said means, and a support for carrying the bucket into loading position, said support being pivoted to swing about a fixed horizontal axis, a discharge gate rigid with said support, and means for automatically lifting said support and gate when the bucket is raised.
6. A hoisting apparatus comprising a bucket, a flexible connection for raising and lowering said bucket, attached to the upper end thereof, a bail hinged to the lower end of said bucket, at the rear side thereof, a sheave for holding said connection in position, mounted on the upper end of said bail, a track, wheels for engaging said track, also mounted on the upper end of said bail, and a support for maintaining said bucket in loading position, said support being pivoted to swing about a fixed horizontal axis, a discharge gate rigid with said support, and means for automatically lifting said support and gate when the bucket is raised.
7. A hoisting apparatus comprising a bucket, a track on which said bucket travels up and down, a connection for raising and lowering said bucket, means for discharging into said bucket, a support for causing the bucket to move toward said means, a guide for said connection, and a carrier for said guide, having means for engaging said track, hinged at its lower end to said bucket, said hinge having a shaft, said support and bucket being movable about a common axis coincident with said shaft, when the bucket moves into and out of loading position, and means upon which said support is pivoted, having bearings for receiving said shaft.
8. A hoisting apparatus comprising a track, a bucket movable up and down said track, a flexible connection for raising and lowering said bucket, a bail for said bucket, hinged thereto, a sheave for engaging and holding said connection in position, carried on the upper end of said bail, a support for holding the bucket in loading position, said hinge having a shaft, said support and bucket being movable about a common axis coincident with said shaft, when the bucket moves into and out of loading position, and means upon which said support is pivoted, having bearings for receiving said shaft.
9. A hoisting apparatus comprising a track, a bucket movable up and down said track, a flexible connection for raising and lowering said bucket, a sheave for engaging and holding said connection in position, an element hinged to said bucket, connected with said sheave, and a support for maintaining the bucket in loading position, said hinge having a shaft, said support and bucket being movable about a common axis coincident with said shaft, when the bucket moves into and out of loading position, and means upon which said support is pivoted, having bearings for receiving said shaft.
10. A hoisting apparatus comprising a bucket, a flexible connection for raising and lowering said bucket, means for directing the course of the bucket, a guide for said connection, hinged to said bucket, held to a definite path of travel by said means, and a support for carrying the bucket into loading position, said hinge having a shaft, said support and bucket being movable about a common axis coincident with said shaft, when the bucket moves into and out of loading position, and means upon which said support is pivoted, having bearings for receiving said shaft.
11. A hoisting apparatus comprising a bucket, a flexible connection for raising and lowering said bucket, attached to the upper end thereof, a bail hinged to the lower end of said bucket, at the rear side thereof, a sheave for holding said connection in position, mounted on the upper end of said bail, a track, wheels for engaging said track, also mounted on the upper end of said bail, and a support for maintaining said bucket in loading position, said hinge having a shaft, said support and bucket being movable about a common axis coincident with said shaft, when the bucket moves into and out of loading position, and means upon which said support is pivoted, having bearings for receiving said shaft.
12. A hoisting apparatus comprising a bucket, a track on which said bucket travels up and down, a connection for raising and lowering said bucket, means for discharging into said bucket, a support for causing the bucket to move toward said means, a guide for said connection, and a carrier for said guide, having means for engaging said track, hinged at its lower end to said bucket, said hinge having a shaft, said support and bucket being movable about a common axis coincident with said shaft, when the bucket moves into and out of loading position, and means upon which said support is pivoted, having bearings for receiving said shaft.

- guide, having means for engaging said track, hinged at its lower end to said bucket, said bucket having a pivoted door, means for holding said door in closed position, and 5 means whereby the door is automatically opened when the bucket reaches dumping position.
13. A hoisting apparatus comprising a bucket, a flexible connection for raising and 10 lowering said bucket, means for directing the course of the bucket, a guide for said connection, hinged to said bucket, held to a definite path of travel by said means, and a support for carrying the bucket into loading 15 position, said bucket having a pivoted door, means for holding said door in closed position, and means whereby the door is automatically opened when the bucket reaches dumping position.
14. A hoisting apparatus comprising a bucket, a flexible connection for raising and lowering said bucket, attached to the upper end thereof, a bail hinged to the lower end of said bucket, at the rear side thereof, a 20 sheave for holding said connection in position, mounted on the upper end of said bail, a track, wheels for engaging said track, also mounted on the upper end of said bail, and a support for maintaining said bucket in 25 loading position, said bucket having a pivoted door, means for holding said door in closed position, and means whereby the door is automatically opened when the bucket reaches dumping position.
15. A hoisting apparatus comprising a track, a bucket movable up and down thereon, means whereby the bucket leaves the lower end of said track to assume a loading position, a flexible connection for raising 30 and lowering said bucket, a guide for holding said connection in position when the bucket leaves the track, connected to said bucket, movable relative thereto, and means engaging said track, connected to said guide.
16. A hoisting apparatus comprising a bucket, a door pivoted on said bucket, a member for retaining said door in closed position, pivoted on the bucket, an element rigid with said retainer, means for engaging 35 said element, carried by the door, whereby said door is opened when the retainer is swung down, and devices for automatically operating said retainer when the bucket moves into and out of dumping position.
17. A hoisting apparatus comprising a bucket, a door pivoted on said bucket, a member for retaining said door in closed position, pivoted on the bucket, an element rigid with said retainer, means for engaging 40 said element, carried by the door, whereby said door is opened when the retainer is swung down, and devices for automatically operating said retainer when the bucket moves into and out of dumping position, said door bearing against the retainer at 45 a point below the pivot of the latter, when the bucket is loaded, and said element serving as a counter weight to keep the retainer in upright position.
18. A hoisting apparatus comprising a bucket, a door pivoted on said bucket, a member for retaining said door in closed position, pivoted on the bucket, an element rigid with said retainer, means for engaging said element, carried by the door, whereby said door is opened when the retainer is swung down, and devices for automatically operating said retainer when the bucket moves into and out of dumping position, said devices including a track, and means 50 for engaging said track, carried on the retainer.
19. A hoisting apparatus comprising a bucket, a door pivoted on said bucket, a member for retaining said door in closed position, pivoted on the bucket, an element rigid with said retainer, means for engaging said element, carried by the door, whereby said door is opened when the retainer is swung down, and devices for automatically 55 operating said retainer when the bucket moves into and out of dumping position, said element having a cam shaped engaging edge whereby the door does not close until after the retainer has moved a distance toward the bucket.
20. A hoisting apparatus comprising a pit, a hopper, a track having its lower portion deflected toward said hopper, disposed in said pit, a bucket movable up and down 60 on said track, and means for tilting the bucket into position to receive the discharge from said hopper, co-operating with said deflection of the track to reduce the depth of said pit, a hoisting cable for said bucket, and means for keeping the cable in position 65 while the bucket is loading, movable up and down on said track.
21. A hoisting apparatus comprising a pit, a hopper, a track having its lower portion deflected toward said hopper, disposed in said pit, a bucket movable up and down 70 on said track, and means for tilting the bucket into position to receive the discharge from said hopper, co-operating with said deflection of the track to reduce the depth of said pit, a gate for said bin, and means for opening said gate by the tilting of the bucket.
22. In a bucket elevator, the combination 75 of a bucket, a framework for tilting the bucket, a chute, and a gate for said chute adapted to be gradually opened by the bucket as it is being tilted, said bucket when tilted occupying a position so that the mouth thereof opens squarely to the chute.
23. In a bucket elevator, the combination 80 of a bucket, a framework for tilting the bucket, a chute, and a gate for said chute adapted to be gradually opened by the

bucket as it is being tilted, the arrangement being such that the opening of the gate is produced solely by the weight of the bucket and the gravitational tilting thereof into 5 loading position, said bucket when tilted occupying a position so that the mouth thereof opens squarely to the chute.

Signed by me at Chicago, Cook county, Illinois, this 11th day of February, 1914.
